UNITED STATES PATENT OFFICE.

WILLIAM A. PUNGS, OF DETROIT, MICHIGAN.

BRAKE-BEAM.

SPECIFICATION forming part of Letters Patent No. 606,298, dated June 28, 1898.

Application filed September 20, 1897. Serial No. 652,275. (No model.)

To all whom it may concern:

Be it known that I, WILLIAM A. PUNGS, a citizen of the United States, residing at Detroit, in the county of Wayne and State of Michigan, have invented certain new and useful Improvements in Brake-Beams, of which the following is a specification, reference being had therein to the accompanying drawings.

10 The invention consists in the construction of a brake-beam, and particularly in the following matters: first, the providing of the brake-beam with an extensible strut having a central swivel portion free to turn without 15 adjusting the strut; second, in the construction of that extensible strut and its combination with the brake-levers supported therein, so as to act as a lock for the adjusting means for extending the strut; third, in the construction of the support for the ends of the 20 truss-rod, and, further, in the construction, arrangement, and combination of the various parts, all as more fully hereinafter described and shown.

25 In the drawings, Figure 1 is a perspective view of a brake-beam embodying my invention. Fig. 2 is an enlarged plan view of a little more than half thereof, being partially broken away to illustrate the construction of 30 the strut and the brake-heads. Fig. 3 is a section through an extensible strut of slightly modified form.

35 A is the compression member of the beam. This I have shown of what I consider a desirable cross-section, comprising a central angle-beam portion *a* and vertical flanges *b* at the edges thereof. At the end of the compression member are the brake-heads *B*, which may be of any known or usual construction and are 40 usually adapted to receive the brake-shoes. These brake-heads are preferably socketed, so that the end of the compression member A will fit therein.

45 C is the truss-rod. This truss-rod is preferably provided with the heads *D* at the ends formed integral with the rod itself. It may, however, be provided with screw-threads and nuts in place of these heads, as is customary in such truss-rods.

50 The brake-head is preferably provided with entering slots *E* for the truss-rods and sockets *F*, in which the head or nuts engage.

In case the truss-rod is provided with an integral head it is not necessary that the socket should be provided if means are present 55 to prevent the disengagement of the rod or its head when the strain is put thereon or while it is in use. If nuts are used, then the socket has a double function of holding the truss-rod against displacement and of 60 holding the nuts from turning. Of course in this case a single lock or shoulder would thus hold the nuts as well as the socket in which the nut engages.

The parts thus far described being assembled to tension the truss-rod I use a suitable strut *G*, which draws the parts tightly into the proper positions and gives the necessary tension to the truss-rod, and, if desired, the necessary camber to the compression 70 member. The form of this extensible strut may be varied to suit the manufacturer or the exigencies of the business. I have shown in the drawings two constructions, the preferred construction being that shown in Figs. 75 1 and 2, in which the strut comprises a block *H* on the compression member, a block *I* bearing against the truss-rod, and an intermediate turnbuckle *J*, having pins *K* at the ends engaging interiorly-screw-threaded sockets 80 in the two blocks with right and left hand threads, so that by turning the turnbuckle *J* the tension will be increased or diminished, as desired.

The turnbuckle is provided with a bearing 85 for the brake-lever *L*. This I have shown as formed by means of an aperture *M* through the turnbuckle and suitable bearing for the pivot of the lever therein. This construction is advantageous for two reasons. First, it 90 enables the brake-lever to be turned to incline either to the right or left, and, second, and most important, when the brake-lever is in position for use the turnbuckle cannot be moved, and therefore the tension of the 95 beam cannot be changed. Thus the brake-lever acts, in effect, as a lock for the adjusting means of the strut. In Fig. 3 I have shown the two socketed blocks *H* and *I* and the turnbuckle *J*; but in this case the sockets in the blocks and the pins in the turnbuckle are plain and not screw-threaded, the turnbuckle in this case not forming the adjusting means. The adjusting means in this 100

construction are formed by means of the sleeve O engaging an exterior screw-thread on the socket H.

P is a lock-nut for locking the parts in their 5 adjusted position.

What I claim as my invention is—

1. In a brake-beam, a strut comprising heads bearing on the compression and tension members respectively, adjusting means on 10 one of said heads to adjust the length of the strut and a rocking support for the brake-lever swiveled between the heads, the turning of which does not adjust the strut.
2. In a brake-beam, a strut comprising 15 heads bearing on the compression and tension members respectively and an intermediate adjusting means for adjusting the length of the strut, consisting of a collar screw-threaded on one of the heads and a central portion 20 swiveled between these heads carrying the brake-lever.
3. In a brake-beam, a strut comprising socketed heads, adjusting means screw-threaded on one of said heads and a lock-nut therefor, 25 an intermediate swivel portion having pins

engaging in said socketed heads and a slot M, in which the brake-lever is pivoted.

4. In a brake-beam, the combination of the compression member, a truss-rod, heads or nuts on the ends of the truss-rod, the brake- 30 heads having sockets into which the heads or nuts are drawn and entering slots extending from the middle of the face portion of the brake-head to the sockets for the truss-rod to be passed through and an extensible strut 35 by means of which the truss-rod is tensioned.

5. In a brake-beam, the combination of the compression member, a truss-rod having end heads or nuts, brake-heads having entering slots for the truss-rod and sockets for the 40 heads the base of said sockets being arranged at an angle to the brake-heads so as to be at substantially right angles with the truss-rod when tensioned and an extensible strut.

In testimony whereof I affix my signature 45 in presence of two witnesses.

WILLIAM A. PUNGS.
